UNITED STATES PATENT OFFICE.

WALTER C. BOTT AND OLIVER P. CLEMENS, OF WALLA WALLA, WASHINGTON.

NECKTIE-FASTENER.

1,162,559.

Specification of Letters Patent. Patented Nov. 30, 1915.

Application filed April 3, 1915. Serial No. 19,006.

To all whom it may concern:

Be it known that we, WALTER C. BOTT and OLIVER P. CLEMENS, citizens of the United States, residing at Walla Walla, in the county of Walla Walla and State of Washington, have invented new and useful Improvements in Necktie-Fasteners, of which the following is a specification.

This invention relates to improvements in fasteners and more particularly to that class thereunder known as tie fasteners.

In carrying out the invention, it is our object to provide a device of this character which may be conveniently and readily attached or removed from the collar previous to the untying of the necktie.

A further object of the invention is the provision of a device of the above stated character wherein the fastener may be worn on the upper edge of the overlapping front ends of the collar with the hook portion thereof disposed and retained in a vertical upright position at all times, whereby the said hook will be held against movement upon the grasping of the latter for the purpose of removing or attaching the fastener to said collar.

A still further object of the invention is the provision of a tie fastener whereby the hook portion of the fastener is so connected with the disk portion thereof to prevent any bulk or bulging portion of the collar at the point to which the fastener is attached.

The invention consists of certain novel details of construction, combinations and arrangement of parts as will be now described and pointed out in the appended claim.

In the accompanying drawing:—Figure 1 is a detail perspective view of a collar illustrating our improved fastener connected thereto and detached from the tie. Fig. 2 is a detail perspective view of the fastener detached from the collar. Fig. 3 is a detail vertical section view taken through the front portions of the collar illustrating the manner of attachment of the fastener with such collar. Fig. 4 is a detail vertical section similar to Fig. 3, illustrating the fastener engaged with the scarf or necktie for active use.

Referring more particularly to the various figures of the drawing, A denotes the collar and B the scarf or tie worn thereon.

55 The improved necktie fastener is designated by the reference character 5 and is of

that type to permit the latter to be readily applied to or removed from the overlapping front ends of said collar as the occasion may demand. The fastener in this particular instance includes a thin flat disk 6 which may be made of fiber, celluloid, pearl or other non-corrosive material, to prevent the marring of the collar or the neck of the wearer during the use of the fastener. Said disk is formed with a central opening 7 and grooved through its vertical diameter as at 8.

In order to permit of the fastener being readily attached to and removed from the collar, and to retain it against any accidental movements while being worn, we employ a clasp 9. The clasp shown is formed from a single strand of flexible material composed of metal, wire, and the like of a non-corrosive nature and is bent at one end as at 10 to form an attaching portion. The said portion 10 protrudes through the central aperture 7 of the disk 5 and is terminally bent in engagement with the opposite face of said disk for loosely connecting the clasp to the latter. The said clasp 9 is further bent upwardly and at right angles to its attaching portion 10, to provide a rigid limb 11, the latter terminating above the marginal edge of the disk and thence bent forwardly as at 12, and then downwardly and in spaced relation to the rigid limb 11, to provide a yieldable limb 13. The limbs 11 and 13 and the forwardly bent portion 12 forms an inverted U-shaped collar engaging portion 14, said portion 14 is adapted preferably to straddle the upper edge of the outer overlapped front end 15 of the collar, as shown, whereby preventing the disk of the fastener from engaging the neck of the wearer when being worn, but of course it is understood that the said collar engaging portion may straddle the upper edges of both of the overlapped front ends of said collar and by so doing will retain the collar in closed position and present a neat appearance of the collar on the neck of the wearer. It will be observed that the limb 13 of the U-shaped collar engaging portion is of a length substantially equaling the length of the limb 11 thereof and is curved upwardly in spaced relation thereto as at 15 to form an upstanding tie penetrating hook 16. The groove 8 of the disk 6 is of a depth and width slightly greater than the diameter of the limb 11, whereby the said limb will be snugly seated therein to prevent the

fastener from creating a bulk or bulging effect to the front of the collar when the same is in active position. The seat of the limb 11 in the groove 8 also retains the 5 clasp in a vertical upright position and presents the tie hook for active engagement with the tie B at all times and further prevents any accidental rotation of the clasp when grasping the limbs thereof to remove 10 or attach the fastener to the collar.

From the foregoing description taken in connection with the accompanying drawing, the advantages of the construction and of the method of operation will be readily apparent to those skilled in the art to which 15 the invention relates.

While we have described the principles of operation of the device together with the device which we now consider to be the best 20 embodiment thereof, we desire to have it understood that the device shown is merely illustrative and that such changes may be

made when desired as are within the scope of the claim appended thereto.

What we claim as new is:—

A tie fastener adapted for detachable engagement with the upper edge of a collar comprising a flat disk and a U-shaped clasp loosely connected with said disk, said clasp being bent to provide a collar engaging portion and a tie engaging portion, said disk being formed with a groove extending from its vertical center for receiving the innermost limb of the U-shaped clasp for preventing any accidental movement thereof with 30 respect to said disk.

In testimony whereof we affix our signatures in presence of two witnesses.

WALTER C. BOTT.
OLIVER P. CLEMENS.
